UNITED STATES PATENT OFFICE.

MAURICE G. BENEDICT, OF DETROIT, ASSIGNOR TO THE COLDWATER OIL STOVE COMPANY, OF COLDWATER, MICHIGAN.

OIL-STOVE.

SPECIFICATION forming part of Letters Patent No. 486,063, dated November 8, 1892.

Application filed January 2, 1892. Serial No. 416,787. (No model.)

To all whom it may concern:

Be it known that I, MAURICE G. BENEDICT, a citizen of the United States, residing at Detroit, county of Wayne, State of Michigan, have invented a certain new and useful Improvement in Oil-Stoves; and I declare the following to be a full, clear, and exact description of the invention, such as will enable others skilled in the art to which it pertains to make and use the same, reference being had to the accompanying drawings, which form a part of this specification.

This invention relates to oil-stoves, and has for its object an improvement in the flues by

means of which a constant circulation of fresh air is carried through the stove in contact with highly-heated parts of the stove and thence dispersed throughout the part to be warmed.

The production of a rapid circulation in the air receiving heat from the burner of a stove tends to disperse the heat and equalize the warmth of the apartment within which the stove is located and renders useful in a high degree the heating qualities of the stove. I produce such circulating air by means of the combination of burner and flues shown in the accompanying drawings, in which—

Figure 1 shows in vertical cross-section the complete stove. Fig. 2 shows in horizontal cross-section at the line xx the arrangement of parts comprising the burner and oil-tank surrounding it. Fig. 3 shows the conical terminal flue within which the fresh air passes and is heated.

A represents the base of a stove with walls a extending upward nearly to the height of the burner B. Above the side walls a of the base A other inclosing walls b and c are continued upward as high as may be necessary to inclose all the necessary parts, the walls a b c being fashioned either plain or in any pleasing or ornamental design. Within the inclosing walls a of the base is an oil-tank T, having a central perforation within which rests the burner and its adjuncts. The tank

T is preferably separated from the walls a by a narrow air-space t and is separated from the walls of the burner by an air-space t' , and within this come in order a tubular wall F, an air-space f for feeding air to the flame, a

wick-tube w with double walls W W' , an air-space g , adapted to feed air to the interior of the flame, and a water-tank G. These parts are arranged and constructed in the ordinary way, and they support above the flame the deflecting-ring D and the deflecting-plate d , between which the flame from the burner B passes out into the combustion-chamber K.

The combustion-chamber K forms the central part of the stove. At the upper end of the combustion-chamber K, through the plate or ring H, that forms the partition or division between the central part and the upper part of the stove, is an opening or passage-way k . Within the upper part of the stove and above the opening k is the inner wall of a conical flue E. The conical flue E consists of an outer and an inner cone e e' , united at their base by a perforated ring e^2 . The outer cone is perforated at its top to permit the passage out from it of the air coming into it through the perforations p in the bottom ring. I prefer to have four of these entering pipes or perforations, although the number may be more or less to correspond with the contour or design of the stove adopted. The short pipes p' form legs or supports that hold the double cone E a short distance above the plate H, leaving openings h beneath the base e^2 and between the pipes p' , through which the products of combustion rising from the combustion-chamber K can pass into the outer portion C of the upper compartment and thence through openings c' to the outer air. The short pipes p' rest in or register with short flues or pipes p^2 , that pass from top to bottom through the middle chamber and at their bottom ends rest on or register with the upper ends of flues p^3 , reaching to the base part of the stove below the oil-tank and terminating in bell-mouthed or funnel-shaped openings m . The upper end n of each flue p^3 is perforated through the space above the oil-tank. The flue itself passes through the oil-tank, and the draft of cool air passing through it tends to keep the oil cool.

The operation of the stove is as follows: When the burner is lighted, the heated products of combustion and heated air rise through the mouth k of the combustion-chamber into the cavity beneath the conical face

e of the flue E. It being impossible for them to rise up through this cone, they are deflected and pass down through the openings h into the chamber C and thence into the 5 outer room. In making this travel, however, they heat the plate e to a high degree and the air between e e' becomes highly heated and rises upward, producing a constant inflow of fresh or cold air through the pipes p² 10 p³. The rising current of air through p³ causes the air above the oil-tank T to pass through the perforations n and produces a circulation around the oil-tank, thus aiding in keeping it cool. As the rising air passes 15 out from the pipe p' into the interior of the double cone E it finds an opening much more extended than either the exit e³ or the sum of the entrance-openings p, and consequently the movement of the air is delayed for a short 20 time while in contact with the heated surface of the cone-plates e e', thus allowing it time to take up the heat from those plates before it moves forward, and thus causing the air on its exit to be more highly heated than it 25 otherwise would.

The combustion-chamber K directs the heat centrally upward, compelling it to seek the interior apex of the cone before turning to escape through the openings h.

30 Having thus described my invention, what I claim as novel, and desire to have secured to me by Letters Patent, is—

1. In an oil-stove, the combination of a burner, a combustion-chamber surrounding 35 said burner, a heating-drum above the combustion-chamber, a centrally-perforated partition separating said combustion-chamber from said heating-chamber, a double cone located within the heating-drum and having 40 air-inlets at its bottom leading into the space between the walls of said cone and an air-outlet opening at its apex, and flues connecting the inlet-openings with the space beneath the stove, substantially as and for the purpose 45 specified.

2. In an oil-stove, the combination of a burner, an oil-tank, an air-space being formed above the oil-tank, a flue passing through said oil-tank, terminating at its lower end in 50 a bell-mouth and provided at its upper end with perforated side walls, and a flue extending above the combustion-chamber from the upper end of said first-mentioned flue and communicating with the outer air and adapted 55 to form a communication through the said perforated side walls between the open air-

space above the oil-tank and the air external to said stove, substantially as and for the purpose specified.

3. In an oil-stove, the combination of a 60 burner, a combustion-chamber surrounding said burner, a heating-drum above said combustion-chamber, a centrally-perforated plate dividing the combustion-chamber from the heating-drum, a conical chamber above the 65 combustion-chamber, situated within the heating-drum, having double walls and an interior space between said walls, and a passage-way beneath the walls of said double cone, adapted to permit the exit of the heated products 70 of combustion that rise through the perforated plate and to permit such heated products to pass into the heating-drum external to said coned chamber, substantially as and for the purpose described. 75

4. In an oil-stove, in combination with the burner, a combustion-chamber surrounding said burner, a heating-chamber, a conical chamber within the heating-chamber, a perforated plate separating the heating-chamber 80 from the combustion-chamber, an oil-tank, and cold-air flues extending through said oil-tank from the bottom of the stove and terminating in said conical chamber, substantially as and for the purpose specified. 85

5. In an oil-stove, in combination with a burner, a combustion-chamber, a heating-chamber, a centrally-perforated plate separating said combustion-chamber from said heating-chamber, and an interior heating-chamber with double conical walls, supported 90 on and spaced from the said plate and having an interior conical cavity beneath it and above the central perforation of said plate, substantially as and for the purpose described. 95

6. In an oil-stove, in combination with a burner, a combustion-chamber surrounding said burner, a centrally-perforated plate terminating said combustion-chamber at its upper extremity, a conical chamber having double walls, and a space between said walls, supported above and spaced from said centrally-perforated plate, the said conical chamber being provided with inlet-flues at its base and an outlet-opening at its apex, substantially as and for the purpose described. 100 105

In testimony whereof I sign this specification in the presence of two witnesses.

MAURICE G. BENEDICT.
